W. SCOTT

TONE CLARIFIER FOR MUSICAL INSTRUMENTS

Filed Dec. 15, 1920

Inventor

W. Scott

By *Watson E. Coley, Jr.* Attorney

UNITED STATES PATENT OFFICE.

WALTER SCOTT, OF SHERIDAN, WYOMING.

TONE CLARIFIER FOR MUSICAL INSTRUMENTS.

Application filed December 15, 1920. Serial No. 430,918.

To all whom it may concern:

Be it known that I, WALTER SCOTT, a citizen of the United States, residing at Sheridan, in the county of Sheridan and State of Wyoming, have invented certain new and useful Improvements in Tone Clarifiers for Musical Instruments, of which the following is a specification, reference being had to the accompanying drawings.

- 10 This invention relates to musical instruments, and particularly to the provision of means in a musical instrument whereby the tone produced by the instrument is reinforced and clarified.
- 15 The general object of my invention is to provide means for clarifying and strengthening or reinforcing the tone produced by a musical instrument, this means consisting in the use of stretched coiled springs disposed within the tone chamber of the instrument and extending across the chamber, the invention being applicable to violins, violin-cellos, pianos, megaphones, the amplifying horns or tone chambers of phonographs, and in fact all instruments wherein a musical sound is produced.

Other objects will appear in the course of the following description.

- 20 My invention is illustrated in the accompanying drawings, wherein:

Figure 1 is a sectional view of a violin with my invention applied thereto;

Figure 2 is a longitudinal sectional view of the violin;

- 25 Figure 3 is a fragmentary sectional view of one end of the violin showing the means for tensioning the springs;

- Figure 4 is a longitudinal sectional view of a horn-like instrument, as for instance a megaphone having my invention applied thereto;

Figure 5 is a section on the line 5—5 of Figure 4;

- 30 Referring to these drawings, and particularly to Figure 1, it will be seen that I have illustrated as one embodiment of my invention a violin, designated generally 16, and having the usual strings 17 upon the exterior of the violin, passing over the usual bridge, and connected to the neck 18 in the usual manner. Disposed within the violin and preferably extending longitudinally thereof adjacent to but out of contact with the belly of the violin are a plurality of 35 coiled springs 19.

I am aware of the fact that it has been

proposed in violins to stretch strings within the violin beneath the belly thereof for the purpose of reinforcing the sound, these strings being tuned to harmonize with the regular strings of the instrument and so that the strings will vibrate in unison therewith, but I have found by considerable experiment that coiled springs under slight tension are much more efficient in every way than uncoiled strings, such as strings of catgut or like material commonly used in violins. I have found that if coiled springs under slight tension are placed within the sound chamber of the violin, that is within the violin, these coiled springs will vibrate with the least sound, whereas stretched wires or stretched strings, particularly under the tension necessary to keep them stretched will not vibrate sympathetically to a slight sound and sufficiently to affect the sound produced by the instrument, but will require a much greater degree of sound to vibrate them properly than will be the case where coiled springs are used.

As before stated, the coiled springs 19 are disposed within the violin or other instrument under slight tension. These coiled springs may be of the same gauge of wire but may have a different number of coils to the inch, or the springs may differ from each other as regards the gauge of wire and the number of coils to the inch, or the coils may have different diameters. This difference in the gauge of the wire or in the size of the coils or the number of coils would cause the springs to differ in the degree of resiliency, in other words differ in their elasticity. Preferably the springs will be of wire of different gauges and the coils will be of different diameters for the different strings, and preferably some means will be provided whereby the springs may be kept at a certain tension. Thus I have illustrated in Figure 3 that end of the violin remote from the neck as being provided with turning posts or pins, around which the extremities of the wire strings are wrapped whereby the tension of the wires may be increased or decreased, but this is purely illustrative and I do not wish to be limited to the particular means illustrated for tensioning these wires. These posts are designated 20 in Figure 3.

In Figure 4, I show another embodiment of my invention wherein I have illustrated a megaphone or amplifying horn 22, such as

is used with phonographs or under other circumstances, wherein there is disposed a series of coiled springs 21 which extend transversely across the amplifying chamber or tone chamber and which are attached at their opposite ends to the wall of the amplifying chamber or tone chamber 22, these springs being of different diameters and being under slight tension. I have illustrated the application of my invention to two different forms of instruments, but it is to be understood that these different forms are illustrative of the fact that my invention may be applied to all kinds of sound producing instruments, and I do not wish to be limited to any particular kind of musical instrument. Thus it may be applied to pianos, violins, to the brass instruments of

an orchestra, phonographs, megaphones, organ pipes, and used in many other constructions. 20

I claim:—

A megaphone embodying an outwardly extending body forming a tone chamber and open at its opposite ends, and coiled springs 25 extending parallel to each other transversely to the axis of the tone chamber and attached at their extremities to the wall of the tone chamber, said springs having different relative resilience and being thereby 30 adapted to vibrate sympathetically and reinforce air vibrations created in said tone chamber.

In testimony whereof I hereunto affix my signature.

WALTER SCOTT.
